UNITED STATES PATENT OFFICE.

NICHOLAS F. EGLER, OF CHICAGO, ILLINOIS.

REGENERATIVE FURNACE.

Application filed June 30, 1923. Serial No. 648,808.

To all whom it may concern:

Be it known that I, NICHOLAS F. EGLER, a citizen of the United States, residing at Chicago, in the county of Cook and State of Illinois, have invented new and useful Improvements in Regenerative Furnaces, of which the following is a specification.

This invention relates to reversing regenerative open hearth furnaces and the like and is fully described in the following specification and shown in the accompanying drawings in which:

Figure 1 is a longitudinal vertical section through one end of a furnace equipped with my invention, on the line 1—1 of Fig. 3,

Fig. 2 is a similar view on the line 2—2 of Fig. 3, and

Fig. 3 is a horizontal section on the line 3—3 of Fig. 2.

The furnace of the embodiment shown comprises a furnace having a hearth 10 and roof 11 which communicates through a mixing port 12 and a passage 13 with a slag pocket 14. The end of the furnace also communicates through an air port 15, and one or more passages 16 with the slag pocket 17.

The slag pockets 14 and 17 communicate in a well known manner with regenerative chambers, (not shown), and these in turn through suitable valves communicate with the atmosphere, with the intake end of the furnace, and with a stack on the out end of the furnace.

This furnace is intended particularly for fixed fuels such as natural gas, oils, powdered coal and the like which is introduced into the mixing port 12 through the opening 18. The air in the passage 13 is under pressure which is controlled by the operator while that in the passage 16 is known as "natural air," that is drawn under the draft of the stack.

With this arrangement, the products of combustion on the out end of the furnace divide, the greater part going down through the passages 16 and only a small part going out through the mixing port 12, and passage 13 to the checker work which serves to pre-heat the air for this passage when the furnace is again reversed. For this reason the amount of heat introduced into this checker work in the usual type of furnace is limited and when the passage 13 is again operated on the in end of the furnace the pressure in-

troduced into this passage is limited because of the limited amount of heat which could be introduced into the checker work connected with this passage.

To remedy this defect, I have added one or more passages 19 as shown in Fig. 1 which communicate with the passages 16 through a cross passage 20. A valve 21 is placed in this cross passage which may be raised and lowered by means of a chain 22 passing over the pulley 23. On the in end of the furnace, the valves 21 are closed while the passage 13 is maintained under a considerable air pressure, that is, anything up to about two inches of water. The overhead air fed through the passages 16 is natural air as before.

On the out end of the furnace one or both of the valves 21 are raised so as to permit the products of combustion to pass through the passage 19, through the slag pocket 14 to the checker chamber to which it is connected. In this way a proper balance may be obtained between the heat of the checker chambers supplying the passages 16 and 13, with the result that the air pressure in the mixing port 12 may be maintained to a much greater degree than has heretofore been possible. In this way the rate of combustion may be greatly increased. At the same time the operator is able to exercise a much greater control over both the speed and kind of combustion in the furnace all the time. The passages 19 may be made as large as necessary to contain the necessary heat in the checker chambers connected to the slag pocket 14 and the heat delivered thereto may be controlled by the amount of which the valves 21 are opened.

The cross passage or by-pass flue may be placed at any point from the out end of the furnace itself to a position near the checker chambers or even between these chambers. The purpose of this by-pass is to maintain a balance between the temperature of the two checker chambers at each end of the furnace.

While I have shown and described certain embodiments of my invention, it is to be understood that it is capable of many modifications. Changes therefore in the construction and arrangement may be made without departing from the spirit and scope of the invention as disclosed in the append-

ed claims, in which it is my intention to claim all novelty inherent in my invention as broadly as possible in view of the prior art.

5 I claim:

1. In a reversing regenerative open hearth furnace, a mixing port, an air port above the mixing port, a regenerative chamber communicating with each port, a passage leading from each port to its regenerative chamber, a passage for introducing additional products of combustion from the furnace into the regenerative chamber for the mixing port and means for closing the last named passage on the in-end of the furnace.
- 10 2. In a reversing regenerative open hearth furnace, a mixing port, an air port above the mixing port, a regenerative chamber communicating with each port, a passage leading from each port to its regenerative chamber, a passage for introducing additional products of combustion from the furnace into the regenerative chamber for the mixing port, and means for closing the

- 25

last named passage on the in-end of the furnace.

3. In a reversing regenerative open hearth furnace, a central mixing port, an air port on each side of the mixing port, a regenerative chamber communicating with said mixing port, a regenerative chamber communicating with said air ports, a passage leading from each port to its regenerative chamber, a separate passage adjacent each passage leading to the air port, a cross passage connecting the last named passages, and a valve in each cross passage.

4. In a reversing regenerative open hearth furnace, a mixing port, an air port above the mixing port, a regenerative chamber communicating with each port, a passage leading from each port to its regenerative chamber, a passage for introducing additional products of combustion from the air port into the regenerative chamber for the mixing port, and means for closing the last named passage on the in-end of the furnace.

NICHOLAS F. EGLER.
